REFRACTORY FURNACE FOR TOBACCO BARN

Robert B. Williamson, Bluefield, W. Va.

Application June 5, 1947, Serial No. 752,600

7 Claims. (CL 110—1)

1

This invention relates to furnaces of the type which are put together from prefabricated parts at the place of installation, this application being a continuation-in-part of my pending application Ser. No. 696,507, filed September 12, 1946, now abandoned, for Refractory Furnace for Tobacco Barns.

The general object of the invention is to provide a furnace particularly designed for tobacco barns for the flue-curing of tobacco, made from precast refractory units, each of a weight and size to be easily handled by one man, with adjunctive metal securing and spacing members by which precise longitudinal alignment, parallelism of the furnace side walls, length and width of the furnace, and tightness of the joints are automatically obtained through the nature of the construction, notwithstanding lack of particular skill and experience on the part of the labor assigned to the job of erecting the furnace.

Other objects of the invention will appear as the following description of a preferred and practical embodiment thereof proceeds.

In the drawings which accompany and form a part of the following specification, and in which the same reference characters designate identical parts:

Figure 1 is a perspective view of a furnace embodying the inventive concept, parts being broken away;

Figure 2 is a front end elevation;

Figure 3 is a rear end elevation;

Figure 4 is a vertical section, taken along the line 4—4 of Figure 2;

Figure 5 is a cross-section taken along the line 5—5 of Figure 4;

Figure 6 is a cross-section taken along the line 6—6 of Figure 1.

In the flue curing of tobacco it is customary to place the tobacco in a relatively tightly closed barn in which heat is applied to drive off the moisture and set the color. These barns are provided with one or more furnaces and a system of flues or pipes leading therefrom to distribute the heat and carry off the products of combustion. Such furnaces have heretofore been made of brick, stone, or metal, but in most instances fire brick has been employed. It requires the services of a skilled mason properly to set up a stone or fire brick furnace. Some attempts have been made to construct such furnaces of precast refractory shapes, but such attempts have not heretofore been successful because of the high degree of skill needed to line up the walls of the furnace, which cannot usually be found in the available farm labor.

The present invention provides a furnace made of precast refractory members in the minimum number of diversified forms, which is self-aligning in that the members which form the furnace

2

side walls are identical as to overall size and shape, having the form of rectangular prisms so that they can be set upright in longitudinal sequence upon a level slab or foundation. The side walls may be considered self-aligning, since the side wall members have identically located longitudinal bores so that they can be strung upon longitudinal tie rods, assuring precise longitudinal alignment. Metal spacing plates are provided with equidistant holes which can be slipped on the ends of the tie rods, assuring precise parallelism of the side walls. Sectional arch members are also provided, having the same length as the side wall members, adapted to seat thereupon to form the roof of the furnace, the side wall members and arch members meeting in tongue and groove joints, assuring precise alignment when setting, and the arch members being of Gothic form, facilitating their mutual support. The completed arch is a modified catenary curve construction. It is understood that all of the joints shall be set up in mortar. This preview of the general principles of construction makes obvious the facility with which the furnace can be accurately set up with no more skill or experience than is possessed by the average farm handy man.

Referring now in detail to the drawings, the numeral 1 represents a level poured concrete slab or its equivalent, which is not a part of the furnace structure, but serves as a foundation therefor. This slab is provided with a hole 2, opening upwardly into the combustion chamber of the furnace and downward into an underlying trench 3, indicated in broken lines in Figures 1 and 4, which extends beyond the side of the slab. This is to receive a stoker, the burner of which extends through the hole 2 into the combustion chamber.

The furnace comprises the spaced side walls 4 and 5, each of which is built of a contiguous series of side wall blocks 6. Each of these is identical as a length, height and thickness, and all have the general contour of a rectangular prism. Each has upper and lower parallel bores 7 and 8, identically located for each block in the median plane thereof, and extending longitudinally therethrough. Tie rods 9 pass through the respective aligned upper and lower bores of each series. Vertical metal face plates 10 rest against the front and rear ends of the respective side walls 4 and 5. The face plates 10 are preferably rectangular in shape, and each has a pair of holes centered on a line parallel with the sides of the face plate, to register with the respective upper and lower bores 7 and 8. The ends of the tie rods 9 project through the holes in the face plates.

The width of the furnace is determined and fixed by the metal transverse plates 11, of which there are four, two at the front and two at the

rear. These have holes at their opposite ends and are identical as regards the distance apart of these holes. The ends of the tie rods 9 are passed through the holes in the transverse plates 11. The transverse plates are placed outside of the face plates 10. Nuts 12 screw upon the ends of the tie rods and are tightened against the transverse plates to draw the side wall blocks 6 into tight contact. The face plates 10 distribute the stresses imparted by the tie rods over an extensive surface of the outer ends of the terminal side wall blocks, and prevent the localizing of excessive strains which might cause crushing or cracking of the terminal side wall blocks under conditions of expansion when the furnace is heated.

The side wall blocks are formed with a tongue on one side face and complementary groove on the other, so that adjacent blocks form a tongue and groove joint. It is understood that all of the ceramic pieces constituting the furnace will be set up with mortar joints.

The top faces of the side wall blocks 6 are also grooved so as to form an interlocking joint with the arch members, which are to rest upon them. When the tie rods 9 are under tension, the precise parallel alignment of the furnace side walls and the rectangular shape of the furnace, becomes permanently fixed.

Some tobacco barns have one flue leading from the furnace, others have two, and large barns at times have three. In single flue barns connection is made to the rear of the furnace; double flue barns generally connect to the side; three flue barns utilize a rear connection as well as to the right and left-handed side.

In order to make this furnace adaptable to any one of the conventional flue systems, it has provisions for three flue connections, one in the rear end, and one on each side near the rear. This is done by providing two rear side wall blocks in each row, designated by the reference character 6', with semicircular recesses 13, which match when the blocks 6' are placed into adjacency, forming a complete circular opening 14, one on each side. Two rear end wall blocks 16 are also provided, of the same size and shape as the side wall blocks 6', and being similarly recessed to form a circular end opening 14. It will be observed that the recesses 13, and consequently the circular openings 14, are rabbeted on the outside, forming a bore 17 of relatively small diameter toward the inside, and a counter bore 18 of relatively large diameter toward the outside, thereby defining a collar 19. This forms the end stop for a flue pipe 20, preventing the same from projecting into the heat chamber of the furnace, the collar 19 protecting the pipe 20 from contact by the flames, preventing it from becoming red hot or eventually burned out, and being a fire hazard. If the barn construction is such that only one or two flue connections are made to the furnace, two plugs 21 are furnished of such size and shape as to fit into the large bore 18 and rest against the collar 19. These are selectively placed in such flue openings as are not to be employed, being set up in mortar.

A pair of rectangular posts 22 of the same height as the rear end wall blocks 13 are arranged vertically within the side walls at the front end, contiguous to the respective side walls and flush with the front ends of the side walls. These define between them a restricted rectangular opening 23, into the furnace chamber.

Identical arch shaped filler pieces 24 and 25 at

5 the front and rear rest respectively upon the tops of the posts 22 and upon the rear end blocks 16 and close the end spaces subscribed by the arch members. The filler pieces are set flush with the front and rear faces of the side walls.

10 The roof of the furnace is constituted by arch members 26, each being of the same length as the side wall blocks 6, and of the same thickness. To ease the burden of lifting heavy and unwieldy parts, each arch member is preferably made in 15 four sections, two on each side. A base section 27 has a tongue on one face which fits into the groove in side wall 6 and a groove on the opposite face. This block likewise is used in the peak of 20 the arch on the opposite side. A base section 31 has a tongue on each complementary face to fit into the groove of side wall block 6 and the groove of peak section. A peak section 28 with a tongue 25 on one face and groove on the complementary face completes the closure of the arch.

In erecting the furnace, the rear filler piece 25 is put in place and the rearmost arch sections supported upon it, preferably with their grooved 30 side faces toward the front. The sections of the next adjacent arch member are then put in place with their tongued side faces in juxtaposition to the grooved side faces of the sections of the first erected arch member, being supported by the 35 interlocking of the complementary tongues and grooves. Before the foremost arch member is erected the front filler piece 24 is put in place. The Gothic shape of the arch members enables each side of the arch to mutually support the other more efficiently than in the case of a circular arch.

35 A row of fire bricks 29 rests upon the slab 1 and extends across the furnace chamber at an intermediate point in its length, forming the rear wall of the combustion chamber and having a height less than that of the side walls 4 and 5 so that the combustion products can pass over it freely. It constitutes a barrier to confine the ashes to the forward part of the furnace.

40 While dimensions are not vital to the inventive concept, it is one of the purposes of the invention to make the refractory members of such size and weight that they can be handled by one man. In the exemplary embodiment herein illustrated, the side wall members are twelve inches long, eighteen inches high and four inches thick. The size of the other refractory parts are 45 proportioned to these dimensions and all are within the limits of one-man manipulation. It is contemplated that the joints between all the refractory members shall be set up with mortar, to prevent fire and gas leakage.

45 Figures 1 and 4 show that the front transverse plates 11 are offset from the plane of the front of the side walls by a distance equal to the thickness of the intervening front face plates 10. A metal door 30, of slightly less thickness than the front face plates, slides against the front faces of the posts 22 and filler members 4, being retained by the transverse plates 14. It may be 50 lifted or removed for inspection of the combustion chamber, or for removal of the ashes.

55 While the drawing shows furnace as set up for installation of a stoker, it is contemplated that this same type of furnace could, by the insertion 60 of grates in the front end, be adapted to the use of wood, coal, coke, petroleum, pitch or other solid fuel fired by hand. Likewise, an oil or gas burner could be used as a heat source when such fuel is available.

65 From the above description it is obvious that

the subject furnace can be put together in the barn by a workman of very limited skill and experience, since the provision of the tie rods and transverse spacing plates determines the precise alignment and rectangular size and shape of the furnace base, forming a rigid integrated structure which serves as a guide for the correct positioning of the front post members, rear end wall members, filler members and arch members. A furnace of this construction is tied together by metallic bonds so that it cannot become breached or fall apart in the manner common to locally built brick or stone furnaces, so that fire hazard from this cause is altogether eliminated.

What I claim as my invention is:

1. Furnace comprising spaced parallel side walls, each consisting of a row of contiguous refractory members of uniform width and uniform height, tie rods extending through said rows, transverse spacing plates at the front and rear ends of said side walls extending between the tie rods of the respective side walls, through which the ends of said tie rods extend, nuts for tensioning said tie rods to bring said side walls and spacing plates into a rigid rectangular unit, refractory end wall members of the same height as said side wall members fitted between said side walls at the rear flush with the rear ends thereof, vertical posts of the same height as said end wall members, between said side walls at the front, contiguous thereto and flush with the front end thereof, defining a reduced opening at the front of said furnace, refractory arch members forming the roof of said furnace, each having the same width as said side wall members, bridging the space between said side walls and seated thereupon, the joint between said side wall members and arch members including interdigitating tongues and grooves formed on said members.

2. Furnace as claimed in claim 1, said arch members being each formed of a plurality of contiguous sections having tongue and groove points.

3. Furnace comprising spaced parallel side walls, each consisting of a row of contiguous refractory members of uniform width and uniform height, tie rods extending through each row, transverse spacing plates extending between the respective side walls at their ends, through which plates the ends of said tie rods extend, vertical face plates at the front and rear ends of said side walls through which said tie rods pass, said front face plates being between the ends of said side walls and the front transverse spacing plates, end wall members of the same height as the side wall members fitted between said side walls at the rear and flush with the rear ends thereof, vertical posts of the same height as said side wall members between said side walls at the front, contiguous thereto and flush with the front ends thereof defining a restricted opening at the front of said furnace, refractory arch members having the same width as said side wall members bridging the space between said side walls and seated thereupon, the joint between said side wall members and arch members including interdigitating tongues and grooves formed on said members, refractory filler members upon said posts at the front and said end wall members at the rear, closing the respective spaces between the tops of said posts and the tops of said end wall members and the terminal arch members, and a door slidably vertically between said front transverse spacing plates and the refrac-

tory front of said furnace, across said restricted opening.

4. Furnace comprising spaced parallel side walls, each consisting of a row of contiguous refractory members of uniform width and uniform height, tie rods extending through each row, transverse spacing plates extending between the respective rows at the ends of said side walls through which the ends of said tie rods extend, nuts for tensioning said tie rods to bring said side walls and spacing plates into a rigid rectangular unit, refractory end wall members fitted between said side walls at the rear and flush with the rear ends thereof, said end wall members having their contiguous faces provided with matching semi-circular depressions forming a circular flue opening.

5. Furnace comprising spaced parallel side walls, each consisting of a row of contiguous refractory members of uniform width and uniform height, tie rods extending through each row, front and rear transverse spacing plates extending between the tie rods of the respective rows at the ends of said side walls through which the ends of said tie rods extend, nuts for tensioning said tie rods to bring said side walls and spacing plates into a rigid rectangular unit, refractory end wall members fitted between said side walls at the rear and flush with the rear ends thereof, a pair of adjacent side wall members in each side wall near the rear and a pair of said end wall members, each pair of said members having their contiguous faces provided with matching semi-circular depressions forming a circular flue opening, alternatively usable, and refractory plugs less in number than the number of flue openings, for closing any of said flue openings which are not to be used.

6. Furnace comprising spaced parallel side walls and an intervening rear end wall, said walls being formed of contiguous refractory members of uniform height, a pair of said refractory members being formed on adjacent sides with matching semi-circular depressions defining a circular flue opening, said opening being of stepped diameters, the part of larger diameter facing outwardly, the part of smaller diameter forming a collar functioning as a stop to limit the incursion of a flue pipe fitting within the part of large diameter.

7. Furnace as claimed in claim 1, including a refractory filler upon said posts at the front, bridging said posts and closing the space between the top of said posts and the adjacent terminal arch members, and a similar filler member at the rear upon said end wall members, closing the space between the tops of said end wall members and the terminal arch members adjacent thereto.
